UNITED STATES PATENT OFFICE.

LOUIS P. KOVANDA AND JAY H. HUBBELL, OF LOS ANGELES, CALIFORNIA; SAID HUBBELL ASSIGNOR TO SAID KOVANDA.

LINING BLOCK FOR SEWERS AND THE LIKE.

Application filed May 21, 1925. Serial No. 31,745.

Our invention relates to lining blocks for sewers and like structures and has for its principal objects, to generally improve upon and simplify the construction of the existing forms of lining blocks; to construct the lining blocks from vitrified earthen material such as clay, and glaze the surfaces thereof so as to render said blocks immune to the action of acids, alkalies and the like, and further, to construct the blocks with grooves along their edges, which grooves are preferably undercut, so as to receive and retain an acid and alkali-proof cement, thereby producing perfect seams or joints between the edges of the blocks, and eliminating the possibility of joint leakage, that might otherwise occur as a result of the action of acids or alkalies on the unprotected edges of the blocks.

20 A further object of our invention is to produce lining blocks for conduits or the like, that have their rear surfaces ribbed and scored or scarified in order to produce a more perfect bond between said blocks and the material of which the body of the conduit or other structure is formed.

With the foregoing and other objects in view, our invention consists in certain features of construction and arrangement of parts that will be hereinafter more fully described and claimed and illustrated in the accompanying drawings in which:

Fig. 1 is a perspective view of a lining block of our improved construction, and which is of the form particularly designed for lining sewers or like conduits.

Fig. 2 is a perspective view of a block embodying our invention and which may be used as a liner for a substantially flat surface.

40 Fig. 3 is a cross sectional view of a portion of a sewer or like conduit that is lined with blocks of our improved construction.

Figs. 4 to 9 inclusive are detail sectional views of modified forms of joints that are formed between the meeting edges of our improved lining blocks.

50 Referring by numerals to the accompanying drawing and particularly to the construction illustrated in Figs. 1, 3 and 4, 10 designates a lining block that is composed of vitrified earthen material (preferably clay) and having its surfaces, or at least its inner surface, or that surface that is exposed when the

block is applied to the conduit or other structure, glazed in any suitable manner.

55 The rear of the block, or that face that is bonded to the body of the conduit or other structure is stepped or provided with ribs or corrugations 11 of suitable shape, and this entire ribbed or corrugated rear face is 60 roughened by scoring or scarifying in order that the block may be more securely anchored to body of the conduit or like structure to which it is applied.

65 The edges of the blocks are formed with grooves or channels 12, and those portions of the body of the block directly above said grooves, or between the grooves and the front surface of the block are cut away so that the front edges of the block are slightly 70 inset relative to the rear edges.

75 As a result of this particular construction, when the lining blocks are assembled, only those portions of the edges of an adjacent pair of the blocks below the grooves 12 there- 80 in, are in direct contact with each other, and a groove or channel that is undercut on both sides, is formed between the meeting edges of the blocks. As illustrated in Figs. 1, 2 and 4, this groove may be substantially dia- 85 mond shape in cross section, or as illustrated in Fig. 5, it may be substantially oval or heart-shape in cross section.

85 In Fig. 6, the groove has the general shape of an inverted letter T.

90 The constructions illustrated in Figs. 7, 8 and 9 are more particularly designed for flat blocks that are intended to be used as liners for floors, walls and other substantially flat structures.

95 In Fig. 7, the blocks are shown with bevelled edges, so as to produce, between said blocks, a V-shaped groove, the depth of which is substantially equal to the thickness of the blocks.

100 In Fig. 8, the front corners only, of the blocks are cut away, or bevelled to form a V-shaped groove having a depth of approximately half the thickness of the blocks.

In Fig. 9, the front corners of the blocks 100 are cut away to form a groove that is substantially rectangular in cross section.

105 The blocks thus constructed are placed on the inner surfaces of sewers or like structures that are generally formed of self-hardening plastic material such as cement or

concrete and, as the rear surfaces of said blocks are ribbed or stepped and scored, said blocks will be very firmly secured and anchored to the structure to which they are applied.

5 The lining blocks are fitted together so that those portions of their edges below the grooves abut each other and, as a result, the grooves 12 are brought into registration so 10 as to produce undercut grooves between the adjacent edges of all the blocks.

15 The undercut grooves are now filled with a suitable packing or calking material, preferably, a self-hardening cement of putty-like consistency, and which is immune to the action of acids, alkalies and gases.

20 Before the filling material or cement has become set and hard, the exposed faces thereof are made flush with the exposed surfaces 25 of the lining blocks, and thus the sewer or like structure, when finished, is provided with a continuous glazed inner surface that is both acid and alkali-proof, particularly at the joints between the lining blocks, where deterioration and leakage due to the corroding action of acids and alkalies would ordinarily occur.

30 Obviously, our improved lining blocks may be made in any desired and practically usable sizes, and they may be curved so as 35 to be used in tubular or cylindrical structures, or made flat so as to serve as liners for the surfaces of floors, walls and other practically flat structures.

35 When used as linings for sewers and like conduits, the blocks may be applied to the inner faces of pipe sections when the same are pre-cast or they may be applied as the structure is produced by monolithic methods.

40 The ribs and grooves on the rear faces of the blocks may be of any desired width and either stepped or of dove-tail shape in cross section.

45 Thus it will be seen that we have provided simple, practical and efficient means for lining sewers and like ducts, and containers, and which lining means is hard, smooth and wear-resisting, as well as impervious to moisture, and immune to the action of acids, alkalies and the like.

50 Our improved blocks are especially valuable as a lining for sewers, inasmuch as the concrete bodies of the latter, if not thoroughly protected, will be attacked and caused to disintegrate under the action of certain gases, acids and alkalies.

55 Obviously, where all the joints between the lining blocks are filled with an acid and alkali-proof cement, it will be impossible for corrosive gases or the like to reach and attack the concrete body of the sewer.

60 We claim as our invention:

65 A lining for sewers and the like, comprising segmental blocks of vitrified earthen material each having portions of its edges adjacent to one of its faces cut away to form grooves, the inner portions of which grooves are undercut so that when two lining blocks are placed edge to edge, an undercut 70 channel is formed between the meeting edges of the two blocks and a filling of acid and alkali proof material within said undercut channel and the relatively narrow mouth thereinto.

75 In testimony whereof we affix our signatures.

LOUIS P. KOVANDA.
JAY H. HUBBELL.
